(57) **CLAIM**

The ornamental design for a USB hub, as shown and described.

DESCRIPTION

Fig. 1.1 is a perspective view of a USB hub showing my new design;

Fig. 1.2 is another perspective view thereof;

Fig. 1.3 is a perspective view of use state;

Fig. 1.4 is a front view thereof;

Fig. 1.5 is a back view thereof;

Fig. 1.6 is a left side view thereof;

Fig. 1.7 is a right side view thereof

Fig. 1.8 is a top plan view thereof; and

Fig. 1.9 is bottom plan view thereof.

The broken lines in the drawings depict portions of the USB hub that form no part of the claimed design.

1 Claim, 9 Drawing Sheets
